UNITED STATES PATENT OFFICE.

LUDWIG CARL FLACCUS, OF NEW YORK, N. Y., ASSIGNOR TO STETTINER CHAMOTTE-FABRIK ACTIEN-GESELLSCHAFT VORM. DIDIER, OF STETTIN, GERMANY, A CORPORATION OF GERMANY.

DEVICE FOR QUENCHING COKE.

1,007,439.

Specification of Letters Patent. Patented Oct. 31, 1911.

Application filed January 14, 1911. Serial No. 602,570.

To all whom it may concern:

Be it known that I, LUDWIG CARL FLACCUS, a subject of the German Emperor, and resident of the borough of Manhattan, city, 5 county, and State of New York, have invented certain new and useful Improvements in Devices for Quenching Coke, of which the following is a specification.

My invention relates to devices adapted 10 for use to quench coke and has for its object to provide an improved spraying arrangement for the above-indicated purpose.

In the preferred form of my invention, described hereinafter, a quenching car is 15 provided with a spraying device which may be operated while the car is standing still or traveling.

The novel features of my invention are 20 pointed out in the appended claim.

Reference is to be had to the accompanying drawings, in which—

Figure 1 is an end elevation of a quenching car provided with my improved spraying device; and Fig. 2 is a side elevation 25 thereof, with parts broken away.

My invention may be applied to cars of any approved construction, and in the drawing I have shown the spraying device in conjunction with a car of a standard make 30 now on the American market. I shall therefore not describe the car structure in detail. The frame A is supported by wheels B running on rails C. These rails are arranged adjacent to a coke-producing plant (not 35 shown) and extend transversely in front of a bench of coke ovens, in the customary manner. Parallel with the track formed by the rails C is arranged a trough or gutter D so arranged as to receive waste water from 40 the various apparatus connected with a coke oven plant, and also the drippings from the quenching car or cars, the floor being suitably inclined for this purpose. Into the gutter D dips the suction pipe E of a pump 45 F, which in the example illustrated is a centrifugal pump driven direct by a suitable motor such as an electric motor G. The suction pipe is shown provided with the usual perforated intake or strainer E'. The 50 pump throws the water taken from the gutter D into the ascending delivery pipe H provided with a transverse branch H'.

With the upper end of the delivery pipe are connected the two horizontal spraying pipes J, parallel with the rails C. These pipes are 55 mounted loosely in stationary water-tight stuffing boxes K, K', so that each pipe may turn or rock about its longitudinal axis. The stuffing boxes K communicate with the delivery pipe H, and the stuffing boxes K' 60 are closed at their outer ends. At a point or points intermediate between the stuffing boxes K, K', the spraying pipes J are suitably supported, as by a ball bearing L. Each of the pipes J is provided with perforations J', a single longitudinal row of 65 these being employed in the specific embodiment shown in the drawing, and in the position illustrated by Fig. 1 the perforations point directly downward. Each of the pipes J is provided with an upward extension or lug J², the two lugs being connected by a rod M so that both pipes will be rocked in unison to an equal extent. One of the pipes has an additional lug J³ extending laterally 70 and pivotally connected at N' with a rod N whose lower end has a pivotal connection at N² with a hand lever O fulcrumed on the frame A at O'. The dotted lines in Fig. 1 show the extreme positions of the lever O, 75 rod M, and lugs J², and also show the angle α (of about 75°) within which the streams or jets discharged from the perforations J' may be directed to one side or the other by the operation of the lever O. 80

The motor G is preferably independent of the motor (not shown) which causes the car to travel on the rails C, so that the spraying device may be operated either while the car is standing still or while it is under way. 90 By swinging the pipes J about their longitudinal axes, a much more rapid and efficient quenching action is secured, since the water will thus reach all portions of the coke. Since the pump takes its supply from a 95 gutter in which the waste water collects, I dispense with the complicated water connections generally required in the case of cars having spraying pipes, and I also effect a material saving in the amount of water 100 required.

To keep the standpipe H filled when the pump is stopped, so that the pump may then be started readily, I provide a check valve P

of any suitable construction in the delivery pipe H, at a point between the pump and the spraying pipes. To facilitate starting the pump, in case water should leak down past the valve P when the operation has been interrupted for a relatively considerable length of time, a small suction pipe R may have its intake end arranged within the pump casing, the other end having a head 10 R' coöperating with a nozzle S' on an air pipe S. This pipe is connected with a compressed air reservoir (not shown) located on the car, and when air is let out of said reservoir through the pipe S, the injector action at R' S' will suck air and water from the pump and the suction pipe E, whereby 15 the starting of the pump is facilitated.

Various modifications may be made without departing from the nature of my invention as specified in the appended claim. 20

I claim:

The combination with a track and a car arranged to travel thereon, of a plurality of spraying pipes carried by said car and mounted to turn about different axes, means 25 for supplying water to said pipes, and means for rocking said pipes in unison.

In testimony whereof, I have signed this specification in the presence of two subscribing witnesses.

LUDWIG CARL FLACCUS.
